UNITED STATES PATENT OFFICE.

JOHN S. TODD, OF HAWLEY, PENNSYLVANIA.

LET-OFF MEANS FOR LOOMS.

Application filed September 7, 1926. Serial No. 133,888.

The means usually employed in looms for controlling the letting-off of the warp includes some form of friction brake device active on the warp-beam, as a rope or ropes in some way held taut with one or more turns thereof around the beam. The friction between the warp-beam and brake device is not always the same, due to changes in atmospheric and other conditions, and in consequence of this, defects occur in the woven fabric which are known to weavers as "shiers", "barres", "starting-marks", etc., and are the result of the shots of filling being not all equally spaced from each other; in short, the variation in resistance opposed to the warp beam fails to be compensated for in the beating-up operation of the reed of the loom, which thus in a series of beats or strokes finds the sheet of woven fabric and warp offering it varying resistance, so that the filling becomes packed in some places tightly, in others loosely. The present invention, which contemplates a novel form of compensator to be used in connection with looms having let-off mechanisms employing friction-brake devices, has entirely overcome the difficulties alluded to, so that regardless of the nature of the material being woven, the amount of tension which the particular weave requires, atmospheric and other conditions, it makes possible the weaving of fabrics entirely devoid of such defects as I have mentioned.

In the drawing,

Fig. 1 is a side elevation of the rear portion of a loom, showing the let-off mechanism and my compensator; and

Fig. 2 is a rear elevation.

The let-off or warp beam 1 is shown mounted in rearward extensions 2 of the loom frame 3; its ends are equipped with the usual peripherally grooved sheaves 4 to receive the turns of the ropes or other flexible friction brake devices.

In the present case each of these devices 5 has one end extending around a pulley 6, mounted at some fixed point (as the floor), and these ends are joined by the spiral spring 7; the other ends of said devices 50 are attached to levers 8 pivoted in suitable brackets 9 and having adjustable weights 10 thereon. Each such device between its ends has one or more turns around one of the sheaves 4, as shown. While I prefer this form of friction-brake let-off mechanism, others of course may be used.

My invention contemplates the employment of two parts, as rollers, around which the warp extends and by which it is maintained in reverse bends, each roller being 60 yieldingly held against movement in the direction in which the warp tends to move it, being here mounted in a lever structure.

The two lever structures are very similar, except that as shown the forward one, 11, is 65 shorter than the other, 12, so a description of one will serve for both. Each comprises two bars or side members 13, a stretcher 14 connecting them rigidly (as the rod shown penetrating them and having clamping nuts 14^a screwed on its ends against opposite sides of the bars), and the mentioned bend-forming part 15; each of these parts is in the present example a roller having end trunnions 15^a journaled in the bars of the 70 corresponding lever structure at their upper ends, that for the lever structure 12 being the actual whip-roll (in such example) of the loom. The lever structures stand in upright position, the shorter one, 11, in advance of the other, 12, and each is fulcrumed on headed studs 16 secured in the loom-frame extension 2, such studs penetrating suitable holes in the bars of the lever structure; the roller 15 of the forward or shorter 75 lever structure is preferably at such a height that the top thereof is about level with the under side of the roller 15 of the other lever structure. The studs 16 are preferably 80 adjustable in horizontal slots 17 in the frame extension 2, and for securing them where adjusted they may be threaded and equipped with clamping nuts 16^a.

The upper or roller-carrying end of each lever structure is normally urged from the 85 corresponding end of the other lever structure by a pair of spiral springs 18, such springs being connected on the one hand to the lower ends of the respective bars and on the other to some fixed point, as the floor. 100

Assume that the brake devices are so set, as by adjusting the weights 10, as to offer a given amount of resistance to the advance of the cloth. This resistance is supposed to be constant in degree, but for the reasons indicated it is not so in practice, so that (without my compensator) the fabric would contain the faults mentioned. But with my compensator present and controlling the warp whenever the resistance of the brake devices becomes excessive (as if they stick to the sheaves 4) still the warp remains 105 110

yieldingly resisted against the forward stroke of the reed, and this resistance is always substantially the same in degree, so that the successive shots of filling are packed with equal pressure by the reed; in other words, the density of the cloth remains uniform or constant.

I am aware that it has been proposed to arrange the whip-roll in a loom so as to be movable forwardly subject to yielding resistance. But in practice I find that such does not operate to produce perfect cloth under all conditions, especially in the weaving of the finer fabrics. In short, I find that it is essential to the production of the very superior results which my invention makes possible that in addition to such a forwardly yielding roller or equivalent part as this forwardly yielding whip-roll there be another and rearwardly yielding roller or equivalent part and that this is best arranged somewhat forward of the warp-beam and so that the stretch 19 of warp between the two rollers will extend substantially horizontally, or approximately parallel with the main stretch 19^a of the warp; in other words, so that just as the movement of the rearward roller is in the direction of the pull on the stretch 19^a so the movement of the forward roller is in the direction of the pull on stretch 19. While it simplifies the construction and is usually best to mount the parts 15 in levers they may be otherwise supported so as to be capable of the movements mentioned without departing from the spirit of my invention.

Having thus fully described my invention, what I claim is:

1. In combination, with supporting means and a let-off mechanism including, with the revoluble warp-beam, a friction-brake device therefor, a pair of parts around which the warp extends arranged to maintain re-

verse bends in the warp and each normally movable independently of the other under the pressure exerted thereon by the warp in a direction to pass the other, and yielding means normally opposing such movement of each of said parts.

2. In combination, with supporting means and a let-off mechanism including, with the revoluble warp-beam, a friction-brake device therefor, a pair of parts around which the warp extends arranged to maintain reverse bends in the warp and each normally movable independently of the other substantially in the direction in which the portion of the warp extending therefrom is pulled, and yielding means normally opposing such movement of each of said parts.

3. In combination, with supporting means and a let-off mechanism including, with the revoluble warp-beam, a friction-brake device therefor, a pair of lever structures having their fulcra substantially parallel with the axis of the warp beam and having parts around which the warp extends in reverse bends and being normally movable on their fulcra each independently of the other, and yielding means normally opposing movement of the levers in response to pressure exerted on said parts by the warp.

4. In combination, with supporting means and a let-off mechanism including, with a horizontally revoluble warp-beam, a friction brake therefor, a pair of upstanding lever structures having their fulcra horizontal and having at their upper ends parts around which the warp extends in reverse bends and being normally movable on their fulcra each independently of the other, and yielding means normally opposing movement of the levers in response to pressure exerted on said parts by the warp.

In testimony whereof I affix my signature.
JOHN S. TODD.
